CORRESPONDENCE SHEET

Hope Bruce, Washington, D. C.

Application April 20, 1933, Serial No. 667,080

2 Claims. (Cl. 229—92.7)

This invention relates to correspondence sheets, folded and sealed in packet form, will have its corners reinforced with extra thickness of paper such a manner that its corners will be its strongest points. That is to say, to sheets of paper so formed that each sheet may be utilized as a substitute for paper and envelope for correspondence use. Each sheet is so designed that, after a message has been written upon it, it may be folded upon itself and secured in folded position so that the use of an envelope is rendered unnecessary. The packet formed by the folded and secured sheet is of proper size for mailing; the written message is completely enfolded so as to be unviewable from the outside of the packet; and the various layers of paper are maintained in closely held flat relation so that the packet has no greater bulk than has an envelope and correspondence sheet of similar size. It is only necessary to write the address upon the back of the packet and affix a stamp, and it is ready for mailing.

The advantage which a correspondence sheet of this nature possesses over the conventional paper and envelope of corresponding weight and size are primarily its greater economy of production, the cost of the usual envelope being practically eliminated; and its presentation of a great area upon which a message may be written, such portions of the surface as would otherwise constitute the interior of the envelope being made available for message inscription.

The present inventor is well aware that correspondence sheets, in themselves, are by no means new, and that many different forms have been made and tested. None of these, however, despite the inherent advantages which they have possessed, have proven commercially practicable.

Figure 1 is a face view of the inner or rear surface of a correspondence sheet designed in accordance with and embodying the principles of this invention.

Figure 2 is a similar view but showing the sheet after the first folding operation has been effected. Figure 3 is a similar view but showing the sheet after the second folding operation.

Figure 4 is a similar view but showing the sheet after the third folding operation.

Figure 5 is a similar view but showing the sheet after the fourth folding operation and first sealing.

Figure 6 is a similar view but showing the sheet after the fifth and final folding operation.

Figure 7 is a perspective view of the completed packet ready for mailing.

Figures 8 to 14, inclusive, are views similar to Figures 1 to 7, respectively, and illustrating the successive steps in the production of a completed packets without cutting or tearing through the packet from a correspondence sheet according to a modification of the design shown in Figures 1 to 7.

Referring, in the first instance, to Figure 1 of the drawings, there is illustrated a correspondence sheet which consists, basically, of a substantially rectangular sheet of paper so proportioned that when properly folded, it will embody

rectangular zones *a*, *b*, *c*, *d*, *e*, and *f*. These zones are outlined by the dotted lines *m*, *n*, *x*, *y*, and *z* which indicate the lines upon which the sheet is to be folded. These lines may be printed or creased upon the sheet 20 or they may be purely

60

figurative, as described. The zone *a* is flanked, along its upper edge, by a flap *21*, and along its left hand edge by a flap *22*. These flaps are integral with the sheet *20* and are provided, respectively, with gummed portions *23* and *24*.

Between the adjoining ends of the flaps *21* and *22* and outwardly beyond the corner of the zone *a* is formed a small triangular member *25* and at the opposite ends of the flaps are similar triangular members *26* and *27*. The member *26* abuts a corner of the zone *b* and the member *27* abuts a corner of the zone *c*.

After the message is written upon the rear or inner faces of the six zones and upon the front faces of the zones *c*, *d*, *e*, and *f*, if desired, the sheet is folded upon the line *n*, to the position shown in Figure 2, as the first step in the formation of the packet. The next fold is upon the line *m* to the position shown in Figure 3. This is followed by a fold upon the line *x* whereupon the six zones have been brought into superimposed relation as shown in Figure 4. The front face of the zone *a* now forms the front of the packet and the front face of the zone *b* has been folded over to form the rear of the packet. The rear or inner faces of the zones *a* and *b* and both faces of each of the zones *c*, *d*, *e*, and *f* are completely enfolded and covered.

The flap *22* is then folded on the line *y* against the rear of the packet, as shown in Figure 5, its gummed portion *24* being moistened and caused to adhere thereto. The flap *21* is finally folded down on the line *z*, as shown in Figure 6, its gummed portion *23* being moistened and caused to adhere to the rear of the packet. The packet is thus completed, being properly folded and sealed, and is ready for mailing.

It will be noted the zone *a* which forms the front face of the packet has no free edge. Its sides are flanked by the zones *b* and *c* and the flaps *21* and *22*, and its corners are masked by the zone *d* and the small triangular members *25*, *26*, and *27*. In this manner the desired strengthening of the corners of the packet is ensured as each corner will be provided with four folded over superimposed and overlapping layers of paper. The corners of the packet, so reinforced, are thus rendered highly resistant to shocks and strains.

The completed packet presents, between its front and rear faces and at its right hand end, a clear opening *28* as shown in Figure 7. This opening is not intended to be closed as it forms the guide for opening the packet. To open the packet the blade of a paper cutter or pen knife or other suitable and available instrument is inserted into the opening *28* and the flap *21* is cut off along the line of its fold. The flap *22* is then similarly cut after which the sheet is free to be unfolded with no cut or tear upon any portion of the message area.

In that form of the invention illustrated in Figures 8 to 14, inclusive, there is present a certain sacrifice of strength at one of the corners of the packet in order to provide for a more pronounced indication of the opening point. In this form of the invention there is found a sheet *30* having the six zones *a*, *b*, *c*, *d*, *e*, and *f* and adapted to be folded on the lines *n*, *m*, *x*, *y*, and *z*. The sheet is provided with flap *31* having gummed portion *33* and with flap *32* and small triangular

member *37*. In this case there is no reinforcement on the upper left hand corner of the zone *a* but the flap *32* extends downwardly past the end of the zone *a* and flanks the major portion of the zone *b* as well. At the lower left hand corner of the zone *b* a small triangular piece is cut away as shown at *39*.

In the formation of the packet formed from this type of sheet the process is similar to that previously described. However, after the folds have been folded to the position shown in Figure 10, the next step is as shown in Figure 11, wherein the flap *32* is folded over, horizontally, against the rear face of zones *a* and *b*. It is not, however, pasted down as its function is purely to reinforce the edge of the packet and it has no sealing function. After the lower zones have been folded up, as shown in Figure 12, and the flap *31* has been folded down and caused to adhere to the zone *b*, as shown in Figure 13, the triangular cut away portions *39* of the zone is partially exposed at the end of the flap *31* in the form of a smaller triangular opening *40*, as shown in Figures 13 and 14. It is into this opening that the point of the cutter is designed to be inserted in order to cut the flap *31* along its line of fold as thus permits the packet to be unfolded.

It is, of course, obvious that only four zones may occur upon the sheet or if desired, eight or even ten rather than the six that have been illustrated and described. Other modifications and alterations in form and arrangement of parts will readily suggest themselves and even though none such are specifically mentioned herein they are contemplated as forming a part of this invention insofar as they fall within the scope of the following claims:

I claim—

1. A correspondence sheet adapted to be folded and sealed in packet form, said sheet being substantially rectangular and comprising an even numbered equal sized zones adapted to be folded into superimposed flat relation to form the packet, one corner zone forming the rear face thereof, flaps in the form of a trapezoid extending from the free edges of said corner zone and adapted to be folded back thereover, and the zone adapted to form the rear face of the packet and its adjoining flap having a cut away corner whereby when said zone is folded into such packet back forming position and the corresponding flap is folded thereover, an aperture will be presented for the introduction of an appropriate packet opening instrument.

2. A correspondence sheet adapted to be folded and sealed in packet form, said sheet being substantially rectangular and comprising an even number of equal size zones, adapted to be folded into superimposed flat relation to form a packet, one corner zone forming the front face of a packet and an adjoining zone forming the rear face thereof, flaps extending from the free edges of said corner zone and so cut that the flaps are united at one edge whereby reinforcing means is provided for the corner of the folded packet, the corner zone forming the rear face and the adjacent flap having one corner cut therefrom so that when the packet is formed an aperture will be present for the introduction of an appropriate packet opening instrument.

HOPE BRUCE.
